UNITED STATES PATENT OFFICE.

THOMAS HEATH, OF ATTLEBORO, MASSACHUSETTS, ASSIGNOR TO WATSON & NEWELL COMPANY, OF ATTLEBORO, MASSACHUSETTS, A CORPORATION OF RHODE ISLAND.

DESIGN FOR A HANDLE OF SPOONS, FORKS, OR SIMILAR ARTICLES.

No. 40,121.

Specification for Design.

Patented July 6, 1909.

Application filed May 11, 1909. Serial No. 495,372. Term of patent 7 years.

To all whom it may concern:

Be it known that I, THOMAS HEATH, a citizen of the United States, residing in the town of Attleboro, county of Bristol, and Commonwealth of Massachusetts, have invented a new, original, and ornamental Design for the Handle of a Spoon, Fork, or Similar Article, which is illustrated in the accompanying drawing, forming part of this specification.

What I claim is:—

The ornamental design for the handle of a spoon, fork or similar article as shown.

THOMAS HEATH.
